HEAT EXCHANGERS HAVING
PLATE-TYPE FINS

Douglas K. Richardson, Staunton, Va., assignor to Westinghouse Electric Corporation, Pittsburgh, Pa., a corporation of Pennsylvania

Filed Oct. 17, 1966, Ser. No. 587,059
10 Claims. (Cl. 165—179)

ABSTRACT OF THE DISCLOSURE

A heat exchanger has a plurality of spaced-apart fins having a first set of aligned openings, and having a second set of aligned openings spaced from the first set. Interspersed with the fins are other fins, there being a plurality of the first mentioned fins between adjacent ones of the other fins. Alternate ones of the other fins have openings aligned with the openings of the second set, and extend between adjacent openings of the first set. The other ones of the other fins have openings aligned with the openings of the first set, and extend between adjacent openings of the second set. Hollow gaskets have aligned inner edges around the openings, and form spacers between the fins, and seals around the openings.

This invention relates to plate-type heat exchangers in which heat is transferred from one fluid to another fluid, and has an object to increase the heat transfer in such heat exchangers.

A plate-type heat exchanger such as an evaporator coil used as an air cooling coil in a refrigeration system, usually consists of parallel tubes through which refrigerant is circulated, and of closely-spaced parallel, plate-type fins common to such tubes, the expansion of the refrigerant within the tubes absorbing heat from the air passing over the surfaces of the fins.

This invention eliminates the tubes of such a heat exchanger, and substitutes therefor, fin surfaces. In one embodiment of this invention, a plate-type heat exchanger has several spaced-apart sections, each section containing gaskets which space adjacent fins apart, and provide seals. Refrigerant is circulated in a number of passes in a zig-zag path between fins in each section, the sections being connected by return bends at the ends of the heat exchanger.

Among other objects of this invention are to reduce the sizes and costs of plate-type heat exchangers, to reduce the refrigerant charges in refrigeration systems using such heat exchangers as evaporators and condensers, to eliminate refrigerant distributors for evaporator coils, and to eliminate the corrosion which occurs in such heat exchangers when dissimilar metals are used.

This invention will now be described with reference to the annexed drawings, of which:

FIG. 1 is a plan view looking downwardly on FIG. 2;

FIG. 2 is a side elevation of a heat exchanger embodying this invention;

FIG. 3 is a plan view looking upwardly at the bottom of FIG. 2;

FIG. 4 is a plan view of one of the gaskets used in the heat exchanger;

FIG. 5 is an enlarged section along the lines 5—5 of FIG. 1; and

FIG. 6 is an enlarged section along the lines 6—6 of FIG. 1.

Flanges 10, 11, 12 and 13 are longitudinally aligned, and are spaced apart equal distances on the top of the heat exchanger. Similar flanges 14, 15, 16 and 17 are on the bottom of the heat exchanger opposite and aligned with the flanges 10, 11, 12 and 13 respectively. Aligned, parallel, sheet metal fins 20 extend between the flanges 10—14,

2

11—15, 12—16 and 13—17, extend within the spaces between the flanges 10—14, 11—15, 12—16 and 13—17, and have portions extending outwardly beyond the outer flanges. Gaskets 21 having central openings, having inwardly extending end portions 29 with holes 32 therein, and having outer dimensions the same as the flanges, are aligned with and extend between the top flanges 10, 11, 12 and 13 and the top fin 20. Similar gaskets 31 are aligned with the bottom flanges 14, 15, 16 and 17, and extend between the latter and the bottom fin 20. Similar gaskets 21 are aligned with the flanges 10—14, 11—15, 12—16 and 13—17, and extend between adjacent fins 20.

Rods 30 and 31 having threaded ends, extend through end portions of the flanges 10 and 14, extend through the holes 32 in the gaskets 21 between the flanges 10 and 14, and extend through holes in the fins 20 between the flanges 10 and 14. A similar rod 36 extends midway between the rods 30 and 31, through the flanges 10 and 14, and through holes in the fins 20 between the flanges 10 and 14. The rods 30, 31 and 36 have nuts 33, 34 and 37 respectively, threaded against the flanges 10 and 14 sufficiently to compress the gaskets 21 between the latter sufficiently to provide seals between the flanges 10 and 14 and the fins 20 where they are contacted by the gaskets 21 between the flanges 10 and 14.

Similar rods 40 and 41 extend through end portions of the flanges 11 and 15, extend through the holes 32 in the gaskets 21 between the flanges 11 and 15, and extend through holes in the fins 20 between the flanges 11 and 15. A similar rod 44 extends midway between the rods 40 and 41, through the flanges 11 and 15, and through holes in the fins 20 between the flanges 11 and 15. The rods 40, 41 and 44 have nuts 42, 43 and 45 respectively, threaded against the flanges 11 and 15 sufficiently to compress the gaskets 21 between the latter sufficiently to provide seals between the flanges 11 and 15 and the fins 20 where they are contacted by the gaskets 21 between the flanges 11 and 15.

Similar rods 46 and 47 extend through end portions of the flanges 12 and 16, extend through the holes 32 in the gaskets 21 between the flanges 12 and 16, and extend through holes in the fins 20 between the flanges 12 and 16. A similar rod 50 extends midway between the rods 46 and 47, through the flanges 12 and 16, and through holes in the fins 20 between the flanges 12 and 16. The rods 46, 47 and 50 have nuts 48, 49 and 51 respectively, threaded against the flanges 12 and 16 sufficiently to compress the gaskets 21 between the latter sufficiently to provide seals between the flanges 12 and 16 and the fins 20 where they are contacted by the gaskets 21 between the flanges 12 and 16.

Similar rods 52 and 53 extend through end portions of the flanges 13 and 17, extend through holes 32 in the gaskets 21 between the flanges 13 and 17, and extend through holes in the fins 20 between the flanges 13 and 17. A similar rod 56 extends midway between the rods 52 and 53, through the flanges 13 and 17, and through holes in the fins 20 between the flanges 13 and 17. The rods 52, 53 and 56 have nuts 54, 55 and 57 respectively, threaded against the flanges 13 and 17 sufficiently to compress the gaskets 21 between the latter sufficiently to provide seals between the flanges 13 and 17 and the fins 20 where they are contacted by the gaskets 21 between the flanges 13 and 17.

FIG. 5 is a section through the heat exchanger at the flanges 13 and 17. A section at the flanges 11 and 15 would be similar to FIG. 5. FIG. 6 is a section through the heat exchanger at the flanges 12 and 16. A section at the flanges 10 and 14 would be similar to FIG. 6.

The flange 13 has a fluid inlet opening extending therethrough into which extends fluid inlet tube 60. The flange 17 has a fluid outlet opening extending therethrough into

which extends one end of return bend 61. The flange 16 has a fluid inlet opening extending therethrough into which extends the other end of the return bend 61. The flange 12 has an opening extending therethrough into which extends one end of return bend 62. The flange 11 has an opening extending therethrough into which extends the other end of the return bend 62. The flange 15 has an opening extending therethrough into which extends one end of return bend 63. The flange 14 has an opening extending therethrough into which extends the other end of the return bend 63. The flange 10 has a fluid outlet opening extending therethrough into which extends fluid outlet tube 64.

Referring now to FIG. 5 of the drawings, all of the fins 20 except, counting from the top, the fourth fin 20A, and the twelfth fin 20B, have aligned openings 66 therein below the bottom of the fluid inlet tube 60. All of the fins 20 except, counting from the bottom, the fourth fin 20C, and the twelfth fin 20D, have aligned openings 67 above the end of the return bend 61 where it extends into the flange 17. The fins 20 where they extend between the flanges 11 and 15 are similarly constructed. The fin openings 66 and 67 connect with the interior of the gaskets 21 between the flanges 13 and 17.

The fin 20A which has no opening 66 causes, as shown by the arrows on FIG. 5, the fluid from the inlet tube 60 after it has flowed into the fin openings 66 above the fin 20A, to flow to the left (facing FIG. 5) in four passes into the fin openings 67 above the fin 20D, the uppermost of such passes being between the bottom of the flange 13 and the top fin 20 between its openings 66 and 67, and the other three passes being between adjacent ones of the three top fins 20. The fin 20D which has no opening 67 causes, as shown by the arrows on FIG. 5, the fluid which has flowed into the openings 67, to flow to the right in four passes between adjacent fins into the openings 66 in the fins between the fins 20A and 20B. The fin 20B which has no opening 66 causes, as shown by the arrows on FIG. 5, the fluid which has flowed into the openings 66 between the fins 20A and 20B, to flow to the left in four passes between adjacent fins into the openings 67 in the fins between the fins 20D and 20C. The fin 20C which has no opening 67 causes, as shown by the arrows on FIG. 5, the fluid which has flowed into the openings 67 between the fin 20D and 20C, to flow to the right in four passes between adjacent fins into the openings 66 below the fin 20B, then to flow to the left in four passes into the openings below the fin 20C, and then into the return bend 61. The lowermost of the last mentioned four passes is between the bottom fin 20 and the top of the flange 17, the other three of such passages being between adjacent fins. The fluid flow between the flanges 11 and 15 would be the same as that between the flanges 13 and 17 described in the foregoing.

The fluid flowing into the return bend 61 flows from the latter as shown by FIG. 6 of the drawings. Referring now to FIG. 6, the fins 20 between the flanges 12 and 16, except, counting from the top (facing FIG. 6), the fourth fin 20H, and the twelfth fin 20G, have aligned openings 68 below the return bend 62. The fins 20 between the flanges 12 and 16 except, counting from the bottom, the fourth fin 20E and the twelfth fin 20F, have aligned openings 70 above the return bend 61. The fins where they extend between the flanges 10 and 14 are similarly constructed.

The fin 20E which has no opening 70 causes, as shown by the arrows on FIG. 6, the fluid from the return bend 61 after it has flowed into the fin openings 70 below the fin 20E, to flow to the left (facing FIG. 6) in four passes into the fin openings 68 below the fin 20G, the lowermost of such passages being between the top of the flange 16 and the bottom fin 20 between its openings 70 and 68, and the other three passes being between adjacent ones of the three bottom fins 20. The fin 20G which has no opening 68 causes, as shown by the arrows on FIG. 6,

the fluid which has flowed into the openings 68, to flow to the right in four passes between adjacent fins into the openings 70 in the fins between the fins 20E and 20F. The fin 20F which has no opening 70 causes, as shown by the arrows on FIG. 6, the fluid which has flowed into the openings 70 between the fins 20E and 20F, to flow to the left in four passes between adjacent fins into the openings 68 between the fins 20G and 20H. The fin 20H which has no opening 68 causes, as shown by the arrows on FIG. 6, the fluid which has flowed into the openings 68 between the fins 20G and 20H, to flow to the right in four passes between adjacent fins into the openings 70 above the fin 20F, then to flow to the left in four passes into the openings 68 above the fin 20H, and then into the return bend 62. The uppermost of the last mentioned four passes is between the bottoms of the flange 12 and the top 20, the other three of such passes being between adjacent fins. The fluid flow between the flanges 10 and 14 would be the same as that between the flanges 12 and 16 as described in the foregoing.

The flow through the heat exchanger is seen to be in through the inlet tube 60, then in four passes in a zig-zag path between the flanges 13 and 17 as shown by FIG. 5, then through the return bend 61, then in four passes in a zig-zag path between the flanges 12 and 16 as shown by FIG. 6, then through the return bend 62, then in four passes in a zig-zag path between the flanges 11 and 15 as shown by FIG. 5, then through the return bend 63, then in four passes in a zig-zag path between the flanges 10 and 14 as shown by FIG. 6, and then into the outlet tube 64.

The multiple passes which could be fewer or more than the four passes shown and described, serve the purpose of the usual distributor which, therefore, is not required.

Since tubes are not used within the heat exchanger, its size, weight and cost are reduced. Soldering or other methods of tightly securing fins to tubes for good heat transfer are not required. Dissimilar metals such as copper in tubes, and aluminum in fins, are not required.

Air would be moved by a fan which is not shown, over the surfaces of the fins. The gasketed sections offer less resistance to air flow than the staggered tubes of conventional, plate-type heat exchangers.

What is claimed is:

1. A heat exchanger comprising a plurality of aligned, parallel, spaced-apart fins; flanges extending transverse said heat exchanger opposite the end ones of said fins, said fins extending transversely and longitudinally beyond said flanges, said fins having a first set of aligned openings, and having a second set of aligned openings spaced transversely of said heat exchanger from said first set; a plurality of other fins interspersed with said first mentioned fins and aligned with and parallel to the latter, there being a plurality of said first mentioned fins between said flanges and the ones of said other fins closest to said flanges, and between adjacent ones of said other fins, alternate ones of said other fins having openings aligned with said openings of said second set, and extending between adjacent openings of said first set, the other ones of said other fins having openings aligned with said openings of said second set; and hollow means extending between said fins, having aligned inner edges extending around all of said openings, and forming spacers between said fins, and seals around all of said openings.

2. A heat exchanger as claimed in claim 1 in which said hollow means are gaskets.

3. A heat exchanger as claimed in claim 1 in which one of said flanges has a fluid inlet connecting with said openings of one of said sets, and in which the other one of said flanges has a fluid outlet connecting with said openings of the other one of said sets.

4. A heat exchanger as claimed in claim 3 in which said hollow means are gaskets.

5. A heat exchanger comprising a plurality of aligned,

parallel, spaced-apart fins; flanges extending transverse said heat exchanger opposite the end ones of said fins, said fins extending transversely and longitudinally beyond said flanges, said fins having a first set of aligned openings, and having a second set of aligned openings spaced transversely of said heat exchanger from said first set; a single fin between and spaced from adjacent ones of said fins, there being a plurality of said first mentioned fins between one of said flanges and said single fin, said single fin having an opening aligned with said openings of said second set, and extending between adjacent openings of said first set, a second single fin between and spaced from other adjacent ones of said first mentioned fins, there being a plurality of said first mentioned fins between said single fins, said second fin having openings aligned with said openings of said first set, and extending between adjacent openings of said second set; and hollow means extending between said fins, having aligned inner edges extending around all of said openings, and forming spacers between said fins, and seals around all of said openings.

6. A heat exchanger as claimed in claim 5 in which said hollow means are gaskets.

7. A heat exchanger as claimed in claim 5 in which a third single fin is provided between and spaced from said second fin, there being a plurality of said first mentioned fins between said second and third fins, said third fin having an opening aligned with said openings of said second

5

set, and extending between adjacent openings of said first set; and in which there are hollow means between said third fin and adjacent ones of said first mentioned fins, having an inner edge extending around said last mentioned openings, and forming spacers between said third fin and said last mentioned adjacent ones of said first mentioned fins, and seals around said last mentioned openings.

8. A heat exchanger as claimed in claim 7 in which said last mentioned hollow means are gaskets.

9. A heat exchanger as claimed in claim 7 in which one of said flanges has a fluid inlet connecting with said openings of one of said sets, and in which the other one of said flanges has a fluid outlet connecting with said openings of the other one of said sets.

10. A heat exchanger as claimed in claim 9 in which said last mentioned hollow means are gaskets.
